UNITED STATES PATENT OFFICE.

WILLIAM WATTIE, OF WORCESTER, MASSACHUSETTS, ASSIGNOR TO CROMPTON & KNOWLES LOOM WORKS, A CORPORATION OF MASSACHUSETTS.

PILE-WIRE FOR PILE-FABRIC LOOMS.

1,109,719.

Specification of Letters Patent.

Patented Sept. 8, 1914.

Application filed November 22, 1909. Serial No. 529,174.

To all whom it may concern:

Be it known that I, WILLIAM WATTIE, a citizen of the United States, residing at Worcester, in the county of Worcester and 5 State of Massachusetts, have invented certain new and useful Improvements in Pile-Wires for Pile-Fabric Looms, of which the following is a specification.

My invention relates to a pile wire for 10 pile fabric looms, and to that class of pile fabric looms in which stationary wires are used, over which the pile loops are formed, and which extend in the direction of the length of the warps.

15 My invention particularly relates to an improved construction of the pile wire over which the pile loops are formed, and the upright wire or support which carries the pile wire proper, and more particularly the manner of attaching the pile wire, which is made 20 separate from its support, to said support.

The object of my invention is to improve upon the construction of the pile wires of the type shown and described in U. S. Letters Patent, No. 790,017.

In my improved construction of a pile wire, the pile wire proper, and its support, are made separate from each other, and are rigidly attached together. The upper end 30 of the pile wire support is preferably bent over to form an oblong loop, and the attached end of the pile wire proper is bent or made of angle shape, and extends into said loop, and is rigidly attached thereto by 35 solder, brazing, or welding.

I have shown in the drawing a single improved pile wire embodying my improvements, and a guide strip combined therewith.

40 Referring to the drawing:—Figure 1 is a side view of a pile wire, and its supporting wire, and a guide strip, embodying my improvements, looking in the direction of arrow *a*, Fig. 2, and showing in section the supporting bars. Fig. 2 is an edge view of the parts shown in Fig. 1, looking in the direction of arrow *b*, same figure; the supporting bars are not shown in this figure. Fig. 3 is, on an enlarged scale, a section 45 through the inner end of the pile wire, and the upper end of the supporting wire, on line 3, 3, Fig. 1, looking in the direction of arrow *b*, same figure, and, Fig. 4 shows, on an enlarged scale, the inner end of the pile 55 wire, detached.

In the accompanying drawing, 1 is the pile wire, preferably made of flat metal, and of substantially the shape shown, having the straight end 1' extending in a substantially horizontal plane, over which the pile loops 60 are formed in the usual and well known way, and the upwardly inclined rear portion 1''.

2 is the upright wire or support for the pile wire 1, preferably made of flat metal, and separate from the pile wire 1. The lower end of said upright wire 2 is preferably 65 notched at 2', as shown in Fig. 1, to receive a projection 3' on a transverse bar 3, which is secured by a bolt 4 to the transverse bar 5, to hold the upright wires or supports 2 in 70 position. The upper end of the upright wire or support 2 is bent over to form a loop 2'', see Fig. 3, and the free end of the loop is preferably soldered or brazed, or welded to the main part of the wire or support 2. Within the loop 2'', on the upper 75 end of the wire 2, extends the angle shaped end 1''' on the pile wire 1. The angle shaped end 1''' is rigidly secured within the loop on the upright wire or support 2, by 80 soldering or brazing. By forming the looped upper end of the upright wire or support 2, by bending over the upper end of said wire, a thin strip of metal, of substantially uniform thickness, may be used for 85 the upright wires 2, and the boring or making of a hole through the upper end of the wire for the reception of the end of the pile wire, to be secured therein, is avoided; the bending of the wire produces a substantially 90 wedge shaped upper end on the completed wire, without further manipulation. By this construction of the upright wire or blade, the cost of the upright wires 2 is considerably reduced. The upright wire 2 has 95 in this instance an offset 2''' at its upper end, and has secured to its lower part the lower end of the guide strip 6, in this instance by having the lower edges of said 100 guide strip bent around the upright wire 2, and soldered or otherwise secured thereto. The guide strip 6 is preferably made of thin flat metal and extends upwardly above the upper end of the upright wire or support 2, and is slightly inclined rearwardly, and acts 105 to retain the pile warps in their proper relative position, and to guide them when they are raised over the top of the upright wire or support 2, in the usual and well known way.

The advantages of my improvements in 110

pile wire will be readily appreciated by those skilled in the art. I provide a pile wire for the pile loops, which is made separate from the supporting wire or blade, and 5 is rigidly attached to the upper end of said supporting wire in such a manner that the point of attachment forms a smooth and even surface which does not interfere in any way with the passage of the pile warp on 10 either side of the upper end of the supporting wire. The soldering or brazing, or welding of the attached end of the pile wire within the loop at the upper end of the supporting wire, makes a smooth and 15 secure joint, the two parts being substantially integral. The upper end of the looped end of the supporting wire may be pointed or wedge-shape to form an unobstructed and smooth surface for the pile warp to 20 pass down on either side thereof. The thinness of the upper end of the supporting wire and the attached end of the pile wire, allows a larger number of pile wires to be used in the same space, and gives more space 25 between the individual pile wires for the pile warps, in case a less number of pile wires are used.

It will be understood that the details of construction of my improvements may be 30 varied if desired.

Having thus described my invention, what I claim as new and desire to secure by Letters Patent is:

1. The combination with a pile wire over 35 which the pile loops are formed, and an upright blade made separate therefrom, and having its lower end notched on one edge to receive a projection on a transverse bar to secure said upright blade in position, and

having at its upper end a loop formed by 40 bending over the end of said upright blade, said loop of wedge shape at its upper end, and having the attached end of the pile wire rigidly secured therein, of a guide strip having its upper end free and extending 45 above the attached end of the pile wire, and its lower end secured to the lower part of said upright blade.

2. The combination with a pile wire over 50 which the pile loops are formed, and an upright blade made separate therefrom, and having a loop at its upper end formed by bending over the end of said upright blade, said loop of wedge shape at its upper end, and having the attached end of the pile wire 55 rigidly secured therein, of a guide strip, having its upright end extending above the attached end of the pile wire, and its lower end secured to the lower part of said upright blade.

3. The combination with a pile wire over 60 which the pile loops are formed, and an upright blade made separate therefrom, and having an offset therein, and having a loop at its upper end formed by bending over the end of said upright blade, said loop of wedge shape at its upper end, and having the attached end of the pile wire rigidly secured therein, of a guide strip, having its upright end extending above the attached 70 end of the pile wire, and its lower end secured to the lower part of said upright blade by bending over the edges thereof on said blade.

WILLIAM WATTIE.
